UNITED STATES PATENT OFFICE.

RICHARD SAMUEL REYNOLDS, OF LOUISVILLE, KENTUCKY.

FIBER CONTAINER.

1,299,031.

Specification of Letters Patent.

Patented Apr. 1, 1919.

Application filed October 12, 1918. Serial No. 257,832.

To all whom it may concern:

Be it known that I, RICHARD S. REYNOLDS, a citizen of the United States, residing in the city of Louisville, county of Jefferson, 5 and State of Kentucky, have invented certain new and useful Improvements in Fiber Containers, of which the following is a specification.

This invention relates to fiber containers 10 of the cylindrical type and more especially that class which is built up of numerous layers of fibrous material conjoined with an adhesive.

Tubular fiber containers are made by 15 wrapping a rectangular sheet of suitable material about a form or mandrel, the diameter of which is the same as the inside of the tube to be made, the free end of the sheet being secured to the outer convolution by 20 suitable means such as an adhesive.

When it is desired to produce a more rigid tube the adhesive is applied to all of that portion of the inner surface of the sheet which will come into contact with the outer 25 surface thereof when rolled about the mandrel, care having to be exercised to prevent any of the adhesive getting on that portion of the sheet which contacts with the mandrel, otherwise the tube would adhere there- 30 to and render removal therefrom difficult, without damaging the tube. A number of mandrels have to be provided as it is necessary for the tube to remain thereon until the adhesive has set. This method is carried out 35 by hand, and does not lend itself to quantity production. Machines have been devised to spread the adhesive on the sheet and other machines to wrap the sheet about the mandrel, but the sheets must be fed to the ma- 40 chines by hand and the adhesive must be slow setting or else when the sheets reach the wrapping machine it will not adhere, consequently the machine method is not altogether satisfactory. A method has been de- 45 vised in which continuous strips of material are employed. A strip is wound spirally upon a mandrel, and a second strip, having an adhesive applied to its inner surface, is wound upon the first, covering the contiguous 50 edges of the first strip. This method is adapted to quantity production as it is continuous. The mandrel is supported only at one end and the completed portion of the tube is pushed off of the free end of the 55 mandrel in a continuous length as fast as formed. A quick setting adhesive may be

used, and the mandrel be of such length that the adhesive will be set by the time the end of the mandrel is reached, when the tube will be self supporting, that is the extending portion will not sag of its own weight. The tube is then cut into desired lengths.

The spirally wound tube lends itself to quantity production but is objectionable from other view points. It does not present 65 a smooth exterior as does the straight wound tube. Each strip used, presents at each end, two corners which present initial points for disintegration, and the gap between adjoining edges of the respective convolutions offer 70 lodgment for extraneous matter, and points of engagement for projections with which it may come in contact.

An object of my invention is to provide a container as characterized, which shall be 75 economical in manufacture and durable in service.

A further object is the provision of a method for forming a container, such as characterized, on a quantitative basis.

With the foregoing and other objects in view, the invention consists of the novel method of construction illustrated in the accompanying drawing which forms a part of this specification, wherein is set forth an embodiment of the invention, but it is to be understood that such changes and modifications may be resorted to as come within the scope of the claims appended hereunto.

In the drawings, wherein similar reference characters designate like parts in the several views; Figure 1, is a diagrammatic plan showing the method of forming the spirally wound core: Fig. 2, a diagrammatic plan showing a method of applying the outer layers to the core: Fig. 3, a side elevation of the core; Fig. 4, a perspective view of a tube constructed in accordance with my invention: Fig. 5, a longitudinal section (on an enlarged scale) of one wall of the tube shown 100 in Fig. 4; and Fig. 6, a sectional perspective showing a method of applying an end closure.

Referring now to the drawings, the reference numeral —10— designates a mandrel 105 which is supported at one end by bearings —11—. Upon this mandrel two strips —12, 13— of suitable fibrous material are wound spirally, the lead strip 12 being wound direct upon the mandrel, the following strip 13, being wound upon the lead strip in such relationship thereto that it

covers the joint between the convolutions thereof. An adhesive —14— is applied to the inner surface of the second strip by suitable means, such as a roller —15— just previous to its coming into contact with the lead strip. The process of winding, pushes the formed tube along the mandrel and off of the end thereof. The length of the mandrel is such and the properties of the adhesive such that the adhesive is set by the time the end of the mandrel is reached. As the tube projects beyond the mandrel, a cut off tool —16— swinging on an axis —17— is brought to bear against it severing it into desirable lengths to serve as cores —18— for the container. The core, 18, is then placed upon a mandrel —20— of a winding machine (see Fig. 2) and a web —21— of suitable material is led thereto from a supply roll —22—. The web of paper passes between two rollers —23, 24— by means of which it is drawn from off the roll 22, and pushed forward between two other rollers —25, 26—. A reservoir, or font —28— contains a suitable adhesive which is fed on to the periphery of the upper roller 25 which in turn deposits it on the surface of the web. From the rollers 25, 26 the web, now coated with adhesive, passes over a plate —27— which guides it into engagement with the core 18, on the mandrel 20. A plurality of spring pressed rollers —30, 31— bear upon the outer surface of the web as it is wound on the core, thereby insuring uniform contact and adhesion between the layers thereof. When a desired number of layers have accumulated on the core, the web is severed at a point along the plate 27. The container removed from the mandrel, another core placed thereon and the operation repeated. The container is a finished product for some purposes as it comes from the mandrel of the winding machine. Other purposes require closed ends. These may be applied in any desired manner. In Fig. 6, I have illustrated a closure, or cap —35— as applied to the end of a container. It comprises a center portion which is bounded by an annular channel —36— adapted to fit over the ends of the container. When so fitted on the container, pressure is exerted on the inner and outer walls —37, 38— bounding the channel 36, forcing them against the body of the container walls forming a permanent water tight joint. The web 21, may be of fabric suited to the use to which the container is placed. In making a water proof container I prefer to use a felted material impregnated with an asphaltic compound and an adhesive which is fluent by fusion only. To use an adhesive which is fluent by fusion, means are provided to heat the font 28, said means comprising a gas pipe —32— provided with nipples or burners —33—. The arrangement described herein for winding

both the core and body of the container are illustrative only as any suitable means may be employed for the purpose.

Having thus described my invention so that anyone skilled in the art pertaining thereto can make and use the same,

I claim:

1. A fiber container comprising an inner spirally wound section of even diameter throughout its length, and an outer convolute section conjoined therewith by a water proof adhesive. 75

2. In a cylindrical receptacle, a plurality of adherent spirally wound strips forming a tube of even diameter throughout its 80 length and an outer convolute layer adherent to and covering substantially the entire surface of said tube.

3. A fiber container comprising two sections, each consisting of a plurality of layers 85 of fibrous material, substantially the entire area of the inner surface of each overlying layer being adherent, to an under lying layer, the layers of the inner section being arranged spirally and the other arranged 90 convolutely.

4. A fiber container comprising a spirally wound core of even diameter throughout its length and a convolute layer adherent thereto. 95

5. A cylindrical receptacle comprising a spirally wound core having an outer adherent convolute layer covering substantially its entire surface.

6. A cylindrical receptacle comprising an 100 inner spirally wound core section presenting a substantially smooth surface throughout its extent, and an outer convolute section conjoined therewith.

7. A cylindrical receptacle comprising an 105 inner spirally wound section and an outer convolute section, said sections each comprising a plurality of layers the inner surface of each overlying layer being in contact throughout substantially its entire extent with an underlying layer. 110

8. A cylindrical receptacle comprising a spirally wound core presenting a smooth exterior surface and a plurality of convolute layers of fibrous material conjoined by 115 means of a water proof adhesive compound which becomes adhesive solely by fusion.

9. A cylindrical receptacle comprising a core consisting of a plurality of spirally wound layers and a plurality of superimposed convolutions, each of said layers and convolutions being adherent throughout substantially its entire area to an underlying layer or convolution. 120

10. A cylindrical receptacle comprising 125 an inner spirally wound section and an outer convolute section conjoined by an adhesive compound which becomes adhesive solely by fusion.

11. A cylindrical receptacle comprising 130

an inner spirally wound section and an outer convolute section conjoined by a water proof adhesive compound which becomes adhesive solely by fusion.

5. 12. A cylindrical receptacle comprising a core consisting of a plurality of spirally wound layers of fibrous material and an outer portion consisting of a plurality of convolutions of fibrous sheets—said layers and 10 convolutions conjoined with an adhesive compound which becomes adhesive solely by fusion.

13. The method of forming a cylindrical receptacle consisting in forming a core of 15 spirally wound strips of fibrous material, placing said core on a mandrel, and super-

imposing thereon a plurality of convolutions of a sheet of fibrous material, conjoining said convolutions with each other and with the core by means of an adhesive.

14. The method of forming a cylindrical receptacle consisting in forming a core of spirally wound strips of fibrous material, placing said core on a mandrel and super-imposing thereon a plurality of convolutions 25 of a sheet of fibrous material coating the inner surface of said sheet continuously with an adhesive as applied, and applying pressure to said convolutions as applied whereby they are conjoined with the core and with 30 each other.

RICHARD SAMUEL REYNOLDS.
